[57] CLAIM

The ornamental design for a wheeled tray with handles, as shown and described.

DESCRIPTION

FIG. 1 is a top perspective view of wheeled tray with handles showing my new design, with the handles in a down position;

FIG. 2 is a top perspective view thereof with the handles in an upright position;

FIG. 3 is a top plan view thereof;

FIG. 4 is a bottom plan view thereof;

FIG. 5 is a side elevational view thereof, the opposite side elevational view being a mirror image of that shown;

FIG. 6 is a front elevational view thereof, the rear elevational view being a mirror image of that shown;

FIG. 7 is a top perspective view of a second embodiment of the wheeled tray with handles;

FIG. 8 is a top plan view of FIG. 7;

FIG. 9 is a bottom plan view of FIG. 7; and,

FIG. 10 is a side elevational view of FIG. 7, the opposite side elevational view being a mirror image of that shown.

The front and rear elevational view of the second embodiment is identical to FIG. 6.
